CARTON

James C. Benschoter, Stockton, Calif., assignor to
 Fibreboard Products Inc., San Francisco, Calif.,
 a corporation of Delaware

Application September 10, 1935, Serial No. 39,915

13 Claims. (Cl. 229—23)

My invention relates to a knock-down, fibreboard carton, and particularly to one designed for shipping fragile products such as eggs.

One of the objects of my invention is the provision of a light-weight carton which may be readily knocked down and set up so as to permit the same one to be used many times.

Another object of my invention is the provision of a carton which may be set up quickly 10 without the use of machinery by the manual assembly of simple parts which form a flat package before setting up.

Another object of the invention is the provision of a carton having double walls which 15 insure a greater degree of protection for the contents, and which also increase the stability of the carton so as to permit stacking without danger of crushing.

My invention possesses other objects and features of advantage, some of which, with the foregoing, will be set forth in the following description of my invention. It is to be understood that I do not limit myself to this disclosure of species of my invention, as I may 25 adopt variant embodiments thereof within the scope of the claims.

Referring to the drawing:—

Figure 1 is a perspective view of the shipping carton of my invention, portions being broken 30 away to show the arrangement of the interlocking parts.

Figure 2 is a vertical transverse sectional view of the carton showing the position of the parts in set-up form and with the cover closed.

Figure 3 is a fragmentary sectional view showing the arrangement of the parts at one end of the carton.

Broadly, my invention comprises a carton having a continuous ring or band which forms the 40 outer end and side walls, and in which two crossed liner strips are arranged and interlocked with the ring to provide a carton in which the bottom, end and side walls are double. Means are also provided to hold the cover in closed position; and suitable grips are arranged in the 45 outer end walls to facilitate handling of the filled package. The carton is shipped to the packer and may be stored until use in a flat package requiring a minimum of space. After 50 the carton has been used for a shipment of goods or produce it may readily be knocked down and returned to the packer for reuse. The knock-down of the carton involves only the separation of the three interlocked parts; and the manufacture of the parts ready for assembly is 55

respondingly simple, since it involves nothing more than the cutting of three simple blanks, suitably creasing the blanks for folding, and joining by staples or other desired means, opposite ends of one of the blanks to form a four-sided ring. 5

In greater detail the carton of my invention comprises a strip of fibreboard, provided with transverse creases dividing the strip into panels which form the outer side walls 2 and outer end 10 walls 3. This strip may comprise a single piece of fibreboard, or if the size of the parent sheet from which it is cut is not large enough it may be formed of two or more pieces permanently secured together. 15

I prefer to use a heavy solid fibreboard for the outer walls because of its greater strength, and because it presents an excellent surface for printing. Opposite ends of the piece are connected in any suitable manner such as by staples 20 4, or by stitching, or by an adhesive, to form a continuous four-sided ring.

The blank including the outer side and end walls, is also shaped to include an integral stub flange 5, extending from the lower edge of each 25 end wall 3, and hinged thereto along the crease 6, which permits the flange to fold inwardly when the carton is set up. A similar stub flange 7 is provided at the upper edge of each end wall 3; and is adapted to fold inwardly along the 30 crease 8 when the carton is in use. These flanges, 5 and 7, are relatively short and are the only projections which break the otherwise simple rectangular outline of the blank.

Centrally disposed in the upper portion of each 35 end wall 3 is an elongated slot 9, having a wide tongue 11 formed along its upper boundary as shown to provide a grip or handle which facilitates the handling of the filled carton.

Disposed within the outer ring is a second strip 40 of fibreboard, preferably of the double-faced corrugated type. This strip is also provided with transverse creases which divide the strip into panels forming the inner side walls 12, outer bottom wall 13, and the cover or top 14. The 45 strip is folded into a flat-bottom, U-shape piece; and is then inserted into the outer ring preferably from the bottom, so that the stub flanges 5 are enclosed and lie on the inside and flat against the inside of the bottom 13, and the 50 side walls 12 lie flat against and in registry with the side panels 2. This disposes the cover panel 14 in proper position. Extending from the upper edge of the panel 12, is a flap 16 adapted to fold inwardly along the crease 17 when the carton is 55

in use. A tuck flap 18 is similarly hinged along the crease 19 to the cover 14, at the opposite end of the strip; and when the carton is closed it slips between the outer and inner side walls where its frictional engagement with the walls holds the cover in closed position.

A third strip of fibreboard, preferably of the same stock as the second strip, is provided with transverse creases to permit the strip to be folded into a flat-bottom U-shape piece, which forms the two inner ends 21, and the inner bottom wall 22 of the carton.

When the carton is to be set up, the ring is opened from its collapsed position so that the 15 creases form four parallel corner folds and the adjacent sides are perpendicular to each other. The second strip is then folded into a U-shape piece and slipped through the outer ring from the bottom. As the bottom 13 of the second strip 20 approaches the lower edge of the end wall 3, the stub flanges 5 are pressed inwardly so that the upward movement of the bottom is arrested by contact with the lower surface of the flanges. The walls 12 of the second strip now lie flush 25 against and in registry with the outer side walls 2, providing a liner therefor. The third strip, also folded into a U-shape piece, is disposed within the other two strips with the bottom 22 crossing the outer bottom 13. The bottom 22 30 thus provides a liner for the bottom 13, and the end walls 21 lie flush against and in registry with the outer end walls 3 to provide liners for them. It will also be noted that the bottom 22 bears against the upper surface of the stub flanges 5 so that the stub flanges are interlocked 35 between the two bottoms 13 and 22.

After the packing of the carton has been completed the flanges 7 are folded down across the upper edges of the walls 21; and the flap 16 40 folded inwardly over the ends of the flanges 7. The top 14 is then closed down and the tuck-flap 18 inserted between the inner and outer walls 12 and 2 respectively, to frictionally hold the top in closed position.

It will be noted that the inturned stub flanges 45 5 and 7, which are integral with the outer ring, lie between the adjacent portions of the two crossed pieces forming the bottom and the inner side and end walls; and that this engagement interlocks all three parts securely together, altho it is readily releasable to permit separation of the parts.

In the closed position of the carton the edge 55 folds formed by the transverse creases in each strip are parallel in the same strip, but lie at 90° to the folds in each of the other two strips. The arrangement of the three interlocked strips produces a double walled carton in which the longitudinal axis of each strip as to any given side, lies at 90° to the longitudinal axis of the adjacent strip in that side. Viewed in another way the 60 carton may be considered as three strips, folded and nested together so that their respective longitudinal axes or median lines define three planes intersecting at right-angles to each other.

If desired a central partition 26 is provided to 65 prevent the layers of contained products in one end from sliding into the layers at the other end. When eggs are packed, "flats" are inserted between the layers and at the top and bottom of the carton in accordance with the customary method of packing.

It will be noted that in the filled container, the 70 weight of the contents bearing against the inner and outer bottom walls force them together so

that the stub flanges 5 at each end of the carton are clamped in a secure engagement. Because of this arrangement of the parts, the stub flanges are much shorter than would otherwise be possible. It is found that a flange having a width of 1 1/4" to 2" is sufficient. It will be understood, that the width of this flange has a direct relation to the width, and therefore the cost, of the blank out of which the ring is formed. Because of the inherent limitations in drawings, 10 and the showing of the thickness of the material on a scale which is larger than the true one, the position of the inner and outer walls are shown as they are the first time the carton is set up. It will be obvious that when filled and subjected to pressure, the inner or liner walls will lie flatly against the outer walls so that the spaces between these walls as shown in the drawing, will be eliminated, except close to the separating flap or flanges.

A carton made in accordance with my invention is so strong and rigid that it is especially suitable for shipping eggs. It is made up complete, in the factory; the single stitching or stapling operation being done there. After the 25 contents have been removed from the carton, it may be disassembled by reversing the assembly 30 step and the knocked-down pieces returned in a flat package to the shipper to be set up again, refilled and shipped.

The carton is thus capable of long repeated use, and because of this, and of the ready replaceability of worn or damaged parts, either with new parts or salvaged parts of other cartons, the per-shipment cost of my carton before it is 35 finally worn out and discarded, is reduced almost to the vanishing point. Another factor contributing to this result is the light weight of the 40 carton, a size suitable for thirty dozen eggs weighing 4 lbs. less than a wooden crate of the same capacity. Still another cause of the unusual 45 economy attending the use of my carton, is the simplicity of its parts and manufacture, and the absence of special tools or equipment for its assembly by the user.

I claim:

1. A carton comprising a ring forming outer side and end walls of the carton, a pair of crossed U-shaped pieces disposed within the ring and providing a double bottom and inner walls for 50 the carton, and flanges on the ring interposed between the bottom walls.

2. A carton comprising a ring forming outer side and end walls of the carton, a pair of crossed U-shaped pieces disposed within the ring and providing a double bottom and inner walls for the carton, flanges on the ring interposed between the bottom walls, and a cover hinged on the upper edge of one of the crossed pieces, and on its free edge having a tuck flap disposable between 60 the side walls.

3. A carton comprising a ring forming outer side and end walls of the carton, a pair of crossed U-shaped pieces disposed within the ring and providing a double bottom and inner walls for the carton, a cover hinged on the upper edge of one of the crossed pieces, and on its free edge having a tuck flap disposable between the side walls, and flanges on the ring disposed between the bottom walls and under the cover.

4. A carton comprising a ring forming outer side and end walls of the carton, a pair of crossed U-shaped pieces disposed within the ring and providing a double bottom and inner walls for the carton, one of the crossed pieces having an 75

5 inturned flange on one of its upper edges and a cover flap on the other upper edge, flanges on the ring disposed between the bottom walls and under the cover, and a tuck flap on the cover dis-
5 posable between the side walls and against the inturned flange.

5. A knock-down double walled carton comprising three strips of material creased to divide the strips into panels adapted to form the walls of the 10 crate, one of said strips comprising four outer walls, the second strip comprising two outer and two inner walls, the third strip comprising three inner walls and means on two of said outer walls engaging said second and third strips to prevent 15 disengagement of the parts when the carton is set up.

6. A carton comprising a ring forming outer side and end walls of the carton, a pair of crossed U-shaped pieces disposed within the ring and 20 providing a double bottom and inner walls for the carton, flanges on the ring interposed between the bottom walls, and a cover hinged on the upper edge of one of the crossed pieces.

7. A carton comprising a ring forming outer 25 side and end walls of the carton, a pair of crossed U-shaped pieces disposed within the ring and providing a double bottom and inner walls for the carton, flanges on the ring interposed between the bottom walls, a cover hinged on the upper 30 edge of one of the crossed pieces, and means for securing the cover in closed position.

8. A carton comprising a ring forming outer side and end walls of the carton, a pair of crossed U-shaped pieces disposed within the ring and providing a double bottom and inner walls for the 35 carton, flanges on the ring interposed between the bottom walls, a cover for the carton, and means for securing the cover in closed position.

9. A carton comprising three members folded 40 to form wall panels and nested together, two of the members being rectangular strips and the other member being a closed ring, and stub flanges on the ring member for interlocking the assembled strip members.

45 10. A double walled carton comprising a strip of solid fiberboard creased and folded to form a continuous band comprising the four outer side and end walls of the carton; a second strip of corrugated board creased and folded to nest within the first strip and comprising the outer top and bottom and the inner side walls of the carton; a third strip of corrugated board creased and folded to nest within the other two strips and comprising the inner bottom and inner two end 50 walls and stub flanges on said solid fiberboard strip for interlocking with said second and third strips to prevent disengagement of the parts when the carton is set up.

11. A double walled carton comprising a strip of solid fiberboard creased and folded to form a continuous band comprising the four outer side and end walls of the carton, an inwardly extending flange on each edge of the two outer end walls; a second strip of corrugated board creased and folded to interlock with said flanges of the first strip and comprising the outer top and bottom and the inner side walls of the carton; and a third strip of corrugated board creased and folded to lie within the other two strips in engagement with said flanges and comprising the inner bottom and inner two end walls. 5

12. A double walled carton comprising a strip of solid fiberboard creased and folded to form a continuous band comprising the four outer side and end walls of the carton, an inwardly extending flange on each edge of the two outer end walls; a second strip of corrugated board creased and folded to interlock with the flanges on the lower 10 edges of the end walls of the first strip and comprising the outer top and bottom and two inner side walls of the carton, one end of said strip forming the front inner side wall, and the other 15 end forming the cover for the crate, a flap on the side wall end of the strip adapted to overlie the flanges on the upper edges of the end walls, a tuck-in flap on the edge of the cover adapted to slip between the outer and inner side walls to hold the top in closed position; and a third strip of corrugated board creased and folded to lie within the other two strips and comprising the 20 inner bottom and inner two end walls. 25

13. A double walled carton comprising a strip of solid fiberboard creased and folded to form a continuous band comprising the four outer side and end walls of the carton, an inwardly extending flange on each edge of the two outer end walls; a second strip of corrugated board creased and folded to interlock with the flanges on the lower 30 edges of the end walls of the first strip and comprising the outer top and bottom and two inner side walls of the carton, one end of said strip forming the front inner side wall, and the other 35 end forming the cover for the crate, a flap on the side wall end of the strip adapted to overlie the flanges on the upper edges of the end walls, a tuck-in flap on the edge of the cover adapted to slip between the outer and inner side walls to hold the top in closed position; and a third strip of corrugated board creased and folded to lie within the other two strips and comprising the inner bottom and inner two end walls, the two end 40 edges of said third strip bearing against the in-turned flanges on the upper edge of the end 45 walls to secure the third strip in position. 50

JAMES C. BEN SCHOTER.
